UNITED STATES PATENT OFFICE.

THOMAS I. RANKIN, OF PHILADELPHIA, PENNSYLVANIA, ASSIGNOR TO THE
ABRAM COX STOVE COMPANY, OF SAME PLACE.

DESIGN FOR A HEATING-STOVE.

SPECIFICATION forming part of Design No. 25,447, dated April 28, 1896.

Application filed November 22, 1894. Serial No. 529,653. Term of patent 7 years.

To all whom it may concern:

Be it known that I, THOMAS I. RANKIN, a citizen of the United States, residing in Philadelphia, Pennsylvania, have invented a new and useful Design for Heating-Stoves, of which the following is a specification.

My design for a heating-stove is clearly illustrated in the accompanying drawings, in which—

Figure 1 represents the stove in perspective. Fig. 2 is a front view of the door and door-frame enlarged. Fig. 3 is a view of a panel of the open-work section enlarged, and Fig. 4 is a view of the foot-rail.

The essential features of the design are, first, the ornamental scrolls in the open-work section between the body and base of the stove; second, the ornamentation of the fire-door; third, the ornamentation of the base, and, fourth, the ornamentation of the foot-rails.

The base A has feet *a*, and scroll ornamentation extends around the entire base and down each foot. The ash-pit door *b* has an ornamental scroll at each side and a series of Gothic openings. The body D of the stove is plain, and the ornamental door-frame *d* has a fan-like scroll at the top, a panel at the bottom, and foliated scrolls at each side. The door is surrounded by a quadrangular band and has an ornamental ring at the center, and bars extend from the ring to the quadrangular band.

Between the base and the body of the stove is an open-work section E, consisting of narrow foliated scrolls. The cap F of the stove is ornamented in keeping with the body and base. 35

The foot-rails G each have an open center and an ornamental back, and the rib at the base is connected to the upper portion by side bars having ornamental scrolls. 40

I claim—

1. The design for a heating-stove as herein described and as shown in the accompanying 45 drawings.

2. In a design for a heating-stove the open-work section as herein described and as shown in the accompanying drawings.

3. In a design for a heating-stove the ash- 50 pit door as herein described and as shown in the accompanying drawings.

4. In a design for a heating-stove the fire-door and frame, as herein described and as shown in the accompanying drawings. 55

5. In a design for a heating-stove a foot-rail as herein described and as shown in the accompanying drawings.

In testimony whereof I have signed my name to this specification in the presence of 60 two subscribing witnesses.

THOMAS I. RANKIN.
